UNITED STATES PATENT OFFICE.

WALTER STRANDERS, OF NEW YORK, ASSIGNOR TO EDWARD I. HORSMAN,
OF BROOKLYN, N. Y.

PICTORIAL STORY-BLOCKS.

SPECIFICATION forming part of Letters Patent No. 257,102, dated April 25, 1882.

Application filed March 13, 1882. (No model.)

To all whom it may concern:

Re it known that I, WALTER STRANDERS, of New York, in the county and State of New York, have invented a new and useful Improvement 5 in Pictorial Story-Blocks, of which the following is a specification.

Figures 1, 2, 3, 4, 5, 6, 7, 8, 9, and 10 are face views of my improved toy story-blocks, showing them ranged to produce different pictures.

Fig. 11 is a cross-section of the blocks.

The object of this invention is to produce for the instruction or amusement of children and others blocks or slabs the faces of which shall contain illustrations and inscriptions that will, 15 when properly ranged with reference to one another, produce a series of different pictures and the descriptions or text pertaining thereto. In other words, each of the series of blocks can be turned successively, or in certain 20 prescribed order, to produce different series of pictures in connection with the other blocks; but it is not desired to turn them all at once. The scene in which the different pictures are produced is to remain substantially 25 the same at all times. Thus in the drawings the blocks A, B, C, D, E, and F, which are four-sided prisms, are, when placed side by side, as in Fig. 1, in proper order, printed or painted on the exposed sides *b b* so as to show 30 the illustration of a room; and this room is to be the scene, so to say, for the production of an illustration of the poem known as "Old Mother Hubbard." By turning the blocks B and E from the position shown in Fig. 1 to that 35 shown in Fig. 2 the illustration for the first verse of said poem is obtained—namely, the picture of "Old Mother Hubbard," who has entered through the door *a*, and the picture of the dog on the block E, and in connection with 40 this change of scenery from what appears in Fig. 1 is also exposed on the blocks B and E the explanatory legend, to wit:

45 "Old Mother Hubbard
Went to the cupboard
To get her poor dog a bone.
When she got there
The cupboard was bare,
And so the poor dog had none."

50 For the next verse the blocks B and E have both to be turned back into the position in

which they were in Fig. 1, and the blocks A and D are now turned so as to produce in the original scene the picture shown in Fig. 3, which is illustrative of the second verse of said poem or doggerel; and then to produce the illustration for the third verse the blocks A and D are again turned back to show the representation on the face of Fig. 1, and the blocks C and F are turned to produce the picture of the woman and the dog, as is necessary for the third verse, all as shown in Fig. 4.

For the fourth verse the illustration shown in Fig. 5 is used, the block C being again brought back to show its portion of the original 65 scene, and the blocks A and F are turned so as to expose the required illustration and legend, as shown in Fig. 5. Then for the next verse the blocks A and F are again turned back to the original scene, and the middle 70 blocks, C and D, are turned to show the picture of the woman, the cat, and the dog, as in Fig. 6. Fig. 7 shows that for the next verse the blocks B and E are turned to change the original scene of Fig. 1. Fig. 8 shows that for 75 the seventh verse the blocks C and D are turned to change the original scene. For the eighth verse, which is illustrated in Fig. 9, the blocks B and E are turned to change the original scene, and for the last verse the blocks 80 A and F are turned as shown in Fig. 10. In other words, the transformation is obtained in this fashion: Each of the blocks A B C D E F has each of its sides of the prism painted or covered with a different picture, the faces *b b* 85 *b* of all the blocks, when ranged in front, as in Figs. 1 and 11, producing the foundation-scene, and into this foundation-scene the several pictures can be brought by turning the blocks in the order required, always, however, 90 taking care that for a new transformation the blocks are first brought back to the original scene, so as to expose the faces *b b b*. To make this clear we find, for example, that in Fig. 2 the blocks B and E have been so turned as to 95 expose their faces *d*, while all the other blocks expose their faces *b*. (See Fig. 11.) In Fig. 3 the blocks A and D are turned to expose their faces *d*, while all the other blocks expose their faces *b*. In Fig. 4 the blocks C and F expose 100 their faces *d*, while all the other blocks expose their faces *b*. In Fig. 5 the face *e* of the block

A and the face *e* of the block F are exposed, while all the other blocks show their faces *b*. In Fig. 6 the faces *e* of the blocks C and D are exposed, while all the other blocks show their faces *b*. In Fig. 7 the faces *c* of the blocks B and E are exposed, while all the other blocks show their faces *b*. In Fig. 8 the faces *f* of the blocks C and D are exposed, while all the other blocks show their faces *b*. In Fig. 9 the faces *f* of the blocks B and E are exposed, while all the other blocks show their faces *b*; and in Fig. 10 the faces *f* of the blocks A and F are exposed, while all the other blocks show their faces *b*.

Thus we have used in these ten illustrations all the faces of the several blocks, there being altogether in this example twenty-four faces on the six blocks, out of which I have been able to produce ten different pictures, each picture

containing six faces. Sixty faces are practically produced out of the twenty-four.

It is clear that the invention is applicable to blocks illustrated with different pictures and legends, or either, and that it is not necessary that the blocks should have the exact size and form shown, or that the number of the blocks should be six. Any other number will answer.

I claim—

The pictorial story blocks or slabs A, B, C, &c., having on their faces *b* illustrations of a scene, and on their other faces illustrations adapted to enter into the scene for successive display in said scene, substantially as described.

WALTER STRANDERS.
